UNITED STATES PATENT OFFICE.

EDWARD D. KENDALL, OF ELIZABETH, NEW JERSEY, ASSIGNOR OF ONE-THIRD TO LOUIS T. HAGGIN, OF CLOSTER, NEW JERSEY, MARGARET V. HAGGIN AND ALLAN McCULLOH, OF NEW YORK, N. Y., AND H. ESK. MOLLER, OF MONTCLAIR, NEW JERSEY, EXECUTORS OF JAMES B. HAGGIN, DECEASED, AND ONE-THIRD TO ESTATE OF WILLIAM A. MEGRATH, OF BROOKLYN, NEW YORK.

APPARATUS FOR REFINING HYDROCARBONS.

1,154,517.

Specification of Letters Patent.

Patented Sept. 21, 1915.

Application filed April 29, 1912. Serial No. 694,019.

To all whom it may concern:

Be it known that I, EDWARD D. KENDALL, a citizen of the United States, residing at Elizabeth, in the county of Union and State 5 of New Jersey, have invented new and useful Improvements in Apparatus for Refining Hydrocarbons, of which the following is a specification.

My invention relates to improvements in 10 apparatus for refining liquid hydrocarbons, particularly the distillates from crude petroleum, by means of sulfuric acid and other agents and the objects of my invention are, first, to provide a time-saving, continuous 15 and effective process of refining, requiring comparatively little mechanical power and by which the action of the refining agents may be regulated and equalized and, second, to avoid the use of driven currents of air as 20 a means of agitating and commingling the hydrocarbons and refining agents, which air conveys moisture to the acid, which greedily absorbs the moisture and thereby has its efficiency as a refining agent greatly reduced, 25 and which air forms explosive mixtures by taking up hydrocarbon-vapors and which method of treating with forced currents of air is attended with the further disadvantage that in treating a large volume of hydrocarbon (referring, particularly, to the 30 crude burning-oil or so-called "distillate") with sulfuric acid, the portions of the hydrocarbon first chemically and sufficiently acted on by the acid are again and repeatedly 35 subjected to contact with the acid in order to completely treat the succeeding and later portions of the hydrocarbon, so protracting the time required for agitation, and the said first portions of the hydrocarbon, so "over- 40 treated," acquiring darker color, tend to discolor the entire body of the refined hydrocarbon.

The apparatus is illustrated by the accompanying drawing, in which—

45 Figure 1 is a vertical section of the treating vessels and the accompanying settling tanks and Fig. 2 is a vertical section of the washing vessels and settling tanks.

In the drawing, A and B (Fig. 1) represent 50 two vessels preferably of conical form

and similar in all essential respects: these vessels may be made of any suitable material: for small operations they may be made of chemical stoneware or crude porcelain, but the plant illustrated in the drawing is 55 intended for large operations and the vessels A and B may be constructed as shown, C and C being outer shells of heavy steel or iron plate and c and c inner linings of sheet lead and D and D innermost thick linings of 60 chemical stoneware, or crude porcelain, or other suitable material; the thick perforated end-pieces d, d, d, d, may be made of the same material as D, D, or other suitable material.

Attached to the outside of the shells, C and C are heavy hoops of iron, F, F, F, F, resting in grooves in the peripheries of the rollers indicated by f, f, f, f, which support the vessels A and B and contents thereof.

The vessels A and B, as shown in the drawing, are mounted so that the longitudinal line of the bottom of each is parallel with the level floor, platform, or concrete foundation on which the vessel stands.

The vessels A and B are nearly filled with 75 balls, or rounded pieces, which I will herein refer to as balls, H, H, of chemical stoneware, or glass, or crude porcelain, or other suitable material, the sizes of these balls to 80 be proportioned somewhat to the interior dimensions of the vessels A and B, which vessels are rotated by means of the attached rope-pulleys G and G, for which flanged belt-pulleys, or gearing, may be substituted 85 if required.

The vessels A and B having been charged 90 with the proper respective quantities of the movable balls, H, H, that is to say quantities that will nearly fill the interiors of the said vessels and leave room for pervading movements of the masses of balls when the vessels A and B are rotated, the lead-lined covers L and M are to be bolted over the larger ends (as shown in the drawing) of the vessels A 95 and B; extending from the center of each of these covers is a tubular stuffing box, l and m: a short lead-lined pipe, I, closed at its outer end (as shown in the drawing) passes through the stuffing box l. (The packing 100

in the stuffing boxes may be a composition of soft asbestos, graphite and paraffin). The pipe I receives the outlet-ends of the pipe K and the much smaller pipe k.

5 The smaller and open ends of the rotating vessels A and B enter respective hoods which are the upper parts of the funnels J and j (these may be made entirely of chemical stoneware or porcelain). The lead-linings of the iron or steel shells of A and B, project beyond the said open ends and are turned outward to form flanges, as shown at c', c'. The lower part of each of these funnels enters an opening in the cover of a lead-lined settling-tank, T and t, made of steel or iron, which two tanks are alike, excepting that t may be larger than T; each of these tanks is provided with a lead-lined outlet pipe, P and p, leading from its upper part and with a lead-lined outlet valve and pipe near the bottom; the outlet pipe P finally enters the short pipe i which is like the pipe I and passes through the stuffing box m delivering into the vessel B; a much smaller pipe, O, also enters and delivers into the short pipe i.

The outlet-pipe p, leading from the tank t, connects with a pipe W, (Fig. 2), both pipes delivering into a closed vessel, Q, having two compartments, R and r, the dividing partition between which is open only near the bottom of the said vessel, there providing communication between the two compartments; in each of these compartments are 35 perforated disks or diaphragms, in R and r, all constructed and arranged to act as baffle-plates. The vessel Q may have more than two compartments, all equipped with baffle-plates correspondingly arranged and may be 40 made of any suitable material or materials: it may be made of chemical stoneware, all in one piece of material including the baffle-disks, or it may be made of iron or steel plates, lined with lead, and the perforated 45 disks may be made of chemical stoneware or porcelain, or of lead hardened with a small percentage of antimony. The baffle-disks should, preferably, be made with such projections from one surface of each as shall increase the agitation of liquids passing 50 through the vessel Q and the projections on the disks in R, the first compartment of the said vessel, should extend upward, the projections on the disks in r, the second compartment, extending downward. Liquids entering the vessel Q must pass downward through the first compartment and upward through the second compartment in order to escape from the said vessel through the outlet-pipe w: this pipe w conveys such liquids into a lead-lined settling tank, U, constructed in all respects like the settling tanks T and t, excepting that it may be larger than either. (Before transference to the tank U 65 the liquids may be conveyed from the vessel

Q through a second connected vessel like Q, similarly constructed and equipped with baffle disks, or through a series of such vessels, if required).

The outlet-pipe w, extending from the upper part of the tank U, finally connects with the pipe V, both pipes delivering into a closed vessel, S, which is constructed, and equipped with baffle disks, in all essential respects like the vessel Q. (Two or more such vessels may be connected together in series.) The outlet-pipe s from the vessel S delivers finally into a settling tank Y, constructed like the tanks T, t and U excepting that it need not be lined with lead. The outlet-pipe y, near the upper part of the tank Y conducts to a tank for the storage of liquid.

I will now describe the operation of my process as used for the refining of hydrocarbons, especially the so called distillate or 85 crude burning oil from petroleum.

Referring to the drawing, the distillate is continuously conveyed by the pipe K into the pipe I and the rotating vessel A while the smaller pipe k continuously conveys a 90 regulated small proportion of concentrated sulfuric acid into the pipe I and the vessel A: both liquids pass together through the vessel A and from this vessel into the hooded funnel J: during this passage the rotation of 95 the vessel A and the moving, rolling, obstructing action of the balls within that vessel combine to carry the sulfuric acid to the upper and all parts of the interior of the vessel A and thoroughly commingle the acid 100 and distillate, even with forcible contact: the rolling motion of the balls smears them with acid and also so smears the interior of the vessel A, thus enormously increasing the area of contact of the acid with distillate.

The liquids, filling the interstices of the balls and all interspaces within the vessel A, acting as lubricant, prevent material attrition and, serving as a cushion, prevent injurious impacts of the balls against the innermost lining of the vessel A.

From the vessel A the liquids pass through the funnel J into the settling tank T where the sulfuric acid, with associated matter, quickly subsides and passes out of the tank through the valve and pipe near the bottom of the tank, while the partially treated distillate rises and passes out of the tank through the outlet-pipe P which pipe finally and continuously delivers this distillate into the short pipe i and the rotating vessel B: the pipe O continuously conveys a second supply, in much larger proportion, of sulfuric acid, delivering the same into the vessel B, where the real chemical action of 115 the sulfuric acid on the distillate occurs.

Under the conditions before described, with reference to the vessel A, viz: the thorough commingling of the two liquids by the rotation of the vessel B and by the obstruct-

ing, mixing and rubbing action of the rolling balls therein, the acid being smeared over the moving balls and the innermost surfaces of the vessel B, the distillate is subjected to intimate, thorough and forcible contact with the sulfuric acid over a very large area during its continuous flow through the vessel B. The liquids escape from this vessel B and through the funnel *j* into the lead-lined tank *t* from which the sulfuric acid, with combined matter ("sludge acid"), passes out through the adjusted valve and connected pipe near the bottom of said tank, while the acid-treated distillate escapes through the pipe *p* which pipe connects with the pipe W (Fig. 2) through which flows a continuous current of water, for washing the distillate, in volume preferably greater than the volume of the distillate continuously delivered by the pipe *p*: both liquids pass together into the vessel Q. While passing through the first compartment, R, of the vessel Q the liquids flow tumultuously downward through the baffle-disks therein and when passing through the second compartment, *r*, the flow is upward through the contained baffle-disks, this reversed movement of the water and distillate reversing the tendency to precedence in natural movement due to the different gravities of the two liquids. From the vessel Q the washed distillate and water pass through the outlet pipe *w* into the lead-lined settling tank U: the water subsides and flows out of the tank through the adjusted valve and the pipe near the bottom of the tank and the distillate passes out through the pipe *u* which pipe connects with the pipe V through which flows a continuous current of solution of alkali (preferably of sodium hydroxid, because of its cheapness) and both distillate and alkaline solution are conducted into the vessel S which is constructed in all essential respects like the vessel Q excepting that it may be of somewhat smaller dimensions; in this vessel S the alkaline solution removes the last traces of acid from the distillate. From the vessel S the distillate and alkaline solution pass through the pipe *s* into the settling tank Y from which the alkaline solution flows out through the valve and pipe near the bottom of the tank and the distillate (now "refined oil") passes out through the pipe *y* and is conveyed, by means of pumps or otherwise, to a storage tank or tanks.

Having thus described my apparatus, what I claim is:—

1. In an apparatus for refining hydrocarbons, a rotating vessel containing movable balls, a perforated end piece at each end of the vessel, connections at one end of the vessel for supplying respectively hydrocarbon and sulfuric acid, a hooded funnel extending over the other end of the vessel communicating with a settling tank. 60

2. In an apparatus for refining hydrocarbons, a conical rotating vessel arranged with its lower side horizontal, a perforated disk secured within each end of the vessel, movable balls between said end pieces, a cover for one end of said vessel and outside of the perforated end piece, a pipe connected to said cover, an oil supply pipe and a sulfuric acid supply pipe connected to the first mentioned pipe, a hooded funnel extending over the opposite end of said vessel, communicating with a settling tank. 70 75

3. In an apparatus for refining hydrocarbons, conical rotating vessels arranged in series each having its lower side horizontal, a perforated plate within each end of each of said vessels, movable balls in each vessel between said plates, a cover closing one end of each of said vessels, supply connections secured to each cover for delivering material to be refined and supplying sulfuric acid to each vessel, hoods extending over the other ends of each vessel, communicating respectively with settling tanks. 80 85 90

4. In an apparatus for refining hydrocarbons, a conical rotating vessel arranged with its lower side horizontal, a perforated plate within each end of said vessel, movable balls in the vessel between said plates, a cover closing one end of said vessel, connections secured to said cover for supplying hydrocarbon and sulfuric acid to the vessel, a hooded funnel extending over the other end of the vessel in communication with a settling tank, a closed vessel in communication with the settling tank having a partition dividing said vessel into two compartments, perforated diaphragms in each compartment, an additional supply pipe connected 100 105 to said vessel and an outlet pipe connected to the same.

EDWARD D. KENDALL.
